Specification of Letters Patent.

Patented Feb. 5, 1918.

Application filed June 24, 1916. Serial No. 105,550.

To all whom it may concern:

Be it known that I, NELSON STORY, Jr., a citizen of the United States, and a resident of Bozeman, in the county of Gallatin and 5 State of Montana, have invented a new and useful Improvement in Road-Graders, of which the following is a specification.

My invention is an improvement in road graders, and has for its object to provide 10 mechanism in connection with graders for handling the blade with power derived from the wheels of the grader, wherein the power may be applied to lift the blade to vary the cutting angle thereof, or to swing the blade 15 with respect to the grader.

In the drawings:—

Figure 1 is a side view of a grader provided with the improvement,

Fig. 2 is a rear view,

Fig. 3 is a section through the worm gear, 20 Fig. 4 is a section on the line 4—4 of Fig. 5,

Fig. 5 is a section on the line 5—5 of Fig. 1,

Fig. 6 is a section on the line 6—6 of Fig. 4,

Fig. 7 is a partial top plan view showing the axle shifting mechanism

Fig. 8 is a front view partly in section of 30 the whel and axle connection.

The present embodiment of the invention is shown in connection with a grader having a frame 1, the front axle 2 for supporting the front of the frame and the rear axle 35 3 for supporting the rear of the frame. The usual wheels 4 and 5 are connected with the axles, and one of the wheels 5 of the rear axle is keyed or feathered thereon to turn the axle when the wheel turns. The lower 40 section 6 of the fifth wheel which is connected to the axle 3 is provided with bearings 9, in which the axle 3 is mounted to slide, the bearings being on the under side of the fifth wheel section.

45 As is known, the blades or scarifying mechanism of the machines of the character in question are very difficult to handle, and even though a worker may be conscientious it is only a question of time until he becomes 50 so fatigued that he will neglect the proper handling of the blade because of the great exertion required. While the changes may be slight and of small moment when taken singly yet in the aggregate they constitute 55 the difference between a properly and an im-

properly graded road.

The present invention is designed to relieve the operator of the handling of the blade or scarifier, permitting such handling to be done by the power of the machine, that is, by the motion of the grader. With this object in view a bevel gear wheel 10 is keyed 60 on the axle by means of a feather 11 and a lever 12 is pivoted to the section 6 of the fifth wheel as indicated at 13, the lever extending transversely of the fifth wheel and the lever and the section have coöperating mechanism indicated at 14 for holding the lever in adjusted position. The lever has a ring 15 intermediate its ends and encircling 65 the axle and the hub of the bevel gear 10, and the ring is connected to a ring within a groove in the hub with a pin and slot connection indicated at 16 to permit the lever to move the gear wheel longitudinally of the 70 axle.

This gear 10 meshes with a gear 17 on the lower end of a vertical shaft journaled in a bearing 18 on the frame, and the shaft is provided at its upper end with a bevel gear 19. A countershaft 20 is journaled in bearings 21 on the upper fifth wheel section 7, and a sleeve 22 is mounted to slide on the shaft, the sleeve being keyed or feathered to the shaft. Bevel gears 23 and 23^a are secured to the ends of the sleeve, and these gears are adapted to engage in alternation with the bevel gear 19, the sleeve 22 being of a length and the gears being spaced apart the proper distance for this purpose. 90

A lever 24 is pivoted to a bearing bracket 25 on the frame at one end of the shaft 20, and the lever has latch mechanism coöperating with a toothed quadrant 26 on the bracket for holding the lever in adjusted 95 position. The lever is connected to a ring 27, which is journaled in a groove in the extended end of the sleeve 22 by means of a link 28, the connection being such that by means of the lever either bevel gear 23 or 100 23^a may be engaged with the gear 19.

The ends of the shaft 20 are extended beyond the bearings 21 and each end is provided with a sprocket wheel 29. These wheels 29 are connected by chains 30 with 105 sprocket wheels 31 on the outer ends of stub shafts 32, which are journaled in bearing standards 33 on the frame. These sprocket wheels 31 are loose on the shaft, and each carries one section of a clutch 34, the other 110 section of the clutch being feathered on the shaft 32 and operable by a lever 35 pivoted

to the adjacent standard 33 in such manner that the clutch sections may be connected or disconnected to connect the sprocket wheel to the shaft or to disconnect the same therefrom.

Each shaft 32 is also provided with a hand wheel 36 at its inner end for permitting either side of the scraper support to be raised independently of the other, and worm gear connection is provided for operating each shaft 32. The said mechanism comprises a worm 27 on the shaft 32 and a worm wheel 38 on a shaft 39 which is journaled longitudinally of the frame in the adjacent standard 33, and in a bearing bracket 40 on the frame. Each of these shafts 39 has a crank 41 at its forward end, and each crank is connected to the adjacent side of the upper circle 42 of the blade support to be later described, by means of a link 43. Thus either side of the grader supporting circle may be raised or lowered by means of the shaft 39 connected to the said side.

The shaft carrying the bevel gears 17 and 19 operates a shaft 45 through a bevel gear 44, which as shown more particularly in Fig. 4 is mounted on the shaft 45, which is journaled at right angles to the shaft 20. This bevel gear is keyed on the shaft, and is movable into and out of engagement with the gear wheel 19, by means of a lever 46 pivoted to the frame and engaging an annular groove in the hub of the bevel gear in a well known manner to move the said bevel gear longitudinally of the shaft.

Other shafts 47 and 48 are journaled parallel with the shaft 45 and the said shafts are connected by gears 49 and 50. The shaft 47 is provided with a gear 51 which is adapted to mesh with a long gear 52 feathered on the shaft 45 and moved with respect to the shaft 45, by means of a lever 53^a, which is pivoted to the frame and connected with the hub of the gear wheel. This gear wheel 52 may be engaged with the gear wheel 51 or with the gear wheel 50. When the said wheel is engaged with the gear wheel 51 the shaft 47 will be driven directly, while when the gear wheel 52 is engaged with the gear wheel 50 the shaft 47 will be driven indirectly through the shaft 48.

The shaft 47 is provided with a hand wheel 53, for permitting the blade to be shifted manually, and the said shaft is connected to a stub shaft 54 which operates the circle supporting the blade by means of a telescoping shaft 55, connected to the shaft 54 and to the shaft 47 by universal joint connections 56. The stub shaft 54 which is journaled in bearings 57 on the upper circle 42 is provided with a gear wheel 58, which meshes with a rack 59 on the lower circle 60 in such manner that when the shaft 47 is rotated the circle 60 will be moved angularly with respect to the circle 42. The circles

are mounted in such manner that the lower circle may rotate with respect to the upper circle to vary the position of the blade, and the blade 61 is connected to the lower circle 60 by the usual connecting mechanism 62.

The axle 3 is shifted with respect to the fifth wheel and the frame by the mechanism shown more particularly in Figs. 5 and 7. The said mechanism comprises a collar 64 which is journaled in a groove in the inner end of the hub of one of the wheels 5. A screw 65 extends inwardly from the collar parallel with the axle, and a worm wheel 66 is threaded onto the screw. This worm-wheel is engaged by a worm 67 secured to a crank shaft 67^a, which is journaled in bearings 68 on the lower fifth wheel section. The worm wheel is held from movement with the shaft by means of a fixed bracket 68^a, and it will be evident that when the worm wheel is rotated by means of the shaft 67^a, the wheel will be moved inwardly or outwardly, depending upon the direction of rotation of the worm wheel.

The rear axle is moved angularly by means of the shaft 69. This shaft is arranged in vertical position and is provided at its lower end with a pinion 70 which meshes with rack teeth 71 on the lower section of the fifth wheel section 6. It will be evident that when the shaft 69 is turned, the fifth wheel section will also be turned carrying the axle therewith. By means of the lever 12 the bevel gear wheel 10 may be engaged with the gear wheel 7 or disengaged therefrom to connect the blade shifting mechanism with the wheels.

The operation of the device as a whole is as follows:—When it is desired to shift the long axis of the blade at a greater or less angle with respect to the direction of motion of the grader, the bevel gear 10 is moved until it engages with the bevel gear 17 and the gear wheel 52 is arranged to engage the said wheel with the gear 51 or with the gear 50 depending upon the direction it is desired to shift the blade.

When now the axle 30 rotates the shaft 45 will be driven and the shaft 55 either directly or indirectly therefrom, and the lower circle 60 of the blade support will be rotated in the direction desired. Three notches are provided in the quadrant 26 for engagement by the latch mechanism of the lever 24 to hold the said lever with the sleeve 22 in neutral position or with the gear 23 or 23^a in mesh with the gear 19, as may be desired.

When the gear 23 is in mesh with the gear 19, one shaft 39 will be moved in one direction and the other in the opposite direction to simultaneously lift one side and lower the other side of the blade support. If it is desired only to raise or lower one side, either sprocket wheel 31 may be disengaged

from the adjacent shaft 32. The axle may be shifted by the crank shaft 67 and by the shaft 69.

In practice, the parts are so geared that in about one revolution of the rear wheel the blade may be swung from an angle of 45° to a position perpendicular to the direction of the motion of the grader, and with approximately the same extent of revolution, the blade will be raised or lowered to its full motion. The mechanism is connected with the rear axle for convenience, since the controlling means for the machine is arranged at this point. It is obvious, however, that it might be driven from the front wheels with equal facility.

I claim:—

1. In a road grader, the combination with the main frame, the axles supporting the frame and mounted to swing with respect thereto, the scraper, the rotatably connected circles for supporting the scraper, one circle being connected to the scraper, and the other being suspended from the frame, means for tilting the circles, means for rotating the lower circle on the upper circle, and means for connecting either of the said last-named means to the axle for operating the said means from the axle, said rotating means comprising a pinion journaled radially of the upper circle, the lower circle having rack teeth engaged by the pinion, a driving shaft journaled on the frame, an extensible and contractible con-

necting shaft between the pinion and the driving shaft and having universal joint connections therewith, an operating shaft journaled above the axle and having a releasable driving connection therewith, and means for connecting the driving shaft directly or indirectly to the operating shaft.

2. In a road grader, the combination with the main frame, the axles supporting the frame and mounted to swing with respect thereto, the scraper, the rotatably connected circles for supporting the scraper, one circle being connected to the scraper, and the other being suspended from the frame, means for tilting the circles, means for rotating the lower circle on the upper circle, and means for connecting either of the said last-named means to the axle for operating the said means from the axle, said tilting means comprising shafts journaled at the opposite sides of the frame and longitudinally thereof, each having a radial arm and a connection between each arm and the adjacent side of the upper circle, means for rotating either shaft, an operating shaft having a releasable driving connection with the axle, and means for connecting the operating shaft with the operating means of either of the first-named shafts.
